Application April 19, 1950, Serial No. 9,330

Term of patent 14 years

(Cl. D22—3)

To all whom it may concern:

Be it known that we, Joseph D. Kevorkian and Joseph R. Wolfson, citizens of the United States of America, and residents, respectively, of Philadelphia, in the county of Philadelphia and State of Pennsylvania, and Forest Hills, in the county of Queens and State of New York, have invented a new, original, and ornamental Design for Kitchen Knife or the like, of which the following is a specification, reference being had to the accompanying drawing, forming a part hereof.

We claim:

The ornamental design for kitchen knife or the like, substantially as shown.

JOSEPH D. KEVORKIAN.

JOSEPH R. WOLFSON.
